UNITED STATES PATENT OFFICE.

FRANK F. FORSHEE, OF FLINT, MICHIGAN, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

HEAT-CONTROL SWITCH.

Application filed March 24, 1921. Serial No. 455,007.

My invention relates to quick-break switches and particularly to electromagnetically operated switches, and it has for one of its objects to provide a switch which shall have but one actuating coil.

Another of its objects is to provide a switch which shall have but a single movable actuating coil for closing and for interrupting a circuit controlled by the switch.

10 Another object is to provide an energy-storing means which shall store energy during the first part of the movement of the coil and switch, which stored energy shall be effective to continue and complete the 15 movement of said coil and its associated switch blade.

Another object is to provide a rugged device which shall permit of a substantial amount of wear of the moving parts without affecting the operation of the switch.

Several types of electromagnetically operated switches are known to the art but, in most of these, two stationary coils are used in cooperation with the movable core member which is associated with the switch blade to actuate it to an open and to a closed position.

In practicing my invention, I provide a stationary composite guide and core member on which is mounted a single movable magnetic coil, the coil mounting being so designed as to permit of conducting current from it to the guide member.

I provide a switch member which is pivotally mounted intermediate its length and provide a suitable sliding connection between the blade member and the movable magnet coil. I provide an energy-storing means in the form of a spring which serves 40 also to flexibly connect the movable magnet coil and the blade member. The usual stationary contact terminals are provided to co-operate with the movable contact or blade portion of the switch member, the dimensions of the blade portion and the location of the switch jaws being such that the magnet coil will move over a substantial part of its path of travel before the electric circuit through the magnet coil is interrupted.

In the single sheet of drawings,

Figure 1 is a view, in front elevation, of a device embodying my invention, together

with a schematic representation of a control thermostat, a resistor and an electric supply circuit and

Fig. 2 is a view, in side elevation, of the device embodying my invention.

A base plate 1 of suitable insulating material, substantially square in contour, has a plurality of supporting brackets 2 mounted thereon which are suitably secured to the plate 1 by screws or bolts 3. The supporting brackets 2 are made of relatively thin sheet metal and are of substantially L-shape of a height to co-operate with, and support an elongated composite guide and core member 4. The member 4 comprises a centrally located magnetizable portion 5 and two non-magnetizable end portions 6, the three parts 5 and 6 being suitably secured together, either by welding or by interfitting, to provide a member having a substantially uniform external diameter over its entire length. The member 4 is secured to the supporting brackets 2 by means of suitable screws 7.

A magnet coil 8 is located on the member 4 and comprises, in general, a winding 9, adapted to the voltage of the electric supply circuit with which it is to be connected. The mechanical construction of the magnet coil 8 may be of any kind that may be suitable to withstand the conditions of operation and will be described only with direct reference to the means for conducting the current into and out of the winding 9. A suitable metal head 10 is located at each end of the coil and has a plurality of tongues 11 which may be bent at right angles to its body portion in order to properly locate the member on the end of the magnet coil. A cross-piece 12 is provided which may be suitably secured to each of the end pieces 10 by welding or brazing and which may also be screwed to the top of the magnet coil 8, outside of the winding 9 by screws 13.

A brass bushing 14 is located inside of the magnet coil 8 and is held in proper operative position relatively thereto by means of two metal collars 15. The bushing 14 is hollow and the internal diameter thereof is such as to permit of its being located on the guide member 4 and be movable thereon.

A portion of each of the end members 10 is cut away, as indicated at 16 in Fig. 2, to

provide a substantial clearance space between it and the corresponding collar member 15. One end of the winding 9 is connected to one of the end members 10 and the other end is connected either to one of the collars 15 or to the bushing 14.

A member, indicated by the numeral 17, comprises a relatively wide blade portion 18 and a body portion 19, substantially of U shape, to which the blade portion 18 is suitably secured. The body portion 19 is pivotally mounted on the base plate 1 by means of a stud or bolt 20. The arms of the body portion 19 extend beyond the magnet coil 8 and each arm has a slot 21 therein. The upper end of each arm is bent substantially at right angles as indicated at 22. A bolt or screw 23 is suitably secured to each of the members 12 substantially at the middle of the magnet coil 8 to engage the slot 21 and move freely therein.

An energy-storing device, consisting of a spring 24, provides a flexible resilient connection between the members 22 and 23.

Two stationary terminals 25 are mounted on the base plate 1, each of which is provided with suitable jaws 26 of substantially double-U-shape.

A bar 27 provides an electric connection between the stud 20 and a terminal 28, located at the bottom of the base 1.

A heating element 29 is schematically indicated as being controlled by the switch, and a thermostat 30 is provided to suitably control the actuation of the magnet coil 8. The thermostat 30 cooperates with suitable stationary contact terminals 31 and 32, the contact terminal 32 being the one which is engaged by the thermostat when the temperature is below a predetermined value and the terminal 31 being engaged by it when the temperature reaches or exceeds a predetermined value.

One of the terminals of the resistor 29 is connected to one of the conductors of a supply circuit 33 and also to contact terminal 31 and its other terminal is connected to contact 28. The stationary end of the member 30 is electrically connected to one of the supporting brackets 2. The contact terminal 32 is connected to the other conductor of the supply circuit 33, the other conductor of such circuit being connected to one of the terminals 25. The other terminal 25 is connected to the other conductor of the supply circuit 33, the terminal 31 and one of the terminals of the resistor 29.

If it is assumed that the positions of the magnet coil 8 and the switch member 17 are substantially as indicated by the full lines in Fig. 1, the resistor 29 is being energized by the supply circuit 33.

If the temperature reaches a predetermined value, the thermostat member 30 engages the stationary contact terminal 31 as

indicated in Fig. 1 and completes the control circuit as follows: from one of the conductors of the supply circuit 33 to the left-hand terminal 25, jaw 26, switch blade 18, member 19, bar 20, head 10, through winding 9, then into the bushing 14, to the guide member 4, supporting member 2, thermostat bar 30 and terminal 31 and from there to the other conductor of the supply circuit 33. The magnet coil 8 is, therefore, energized and moves upon the centrally located core member 5 to the left, as indicated by the broken lines in Fig. 1. As the portions 22 of the body portion of the switch move to initially increase the distances between them and the bolts 23, the spring member 24 is expanded and has energy stored therein. As the blade member 18 is relatively wide, the current will continue to traverse the magnet coil and the circuit until the coil reaches substantially its central position on the guide member 4. At this time, the magnet coil 8 and the associated switch member 18 are moving at relatively high speed and, even though the circuit is now interrupted by the disengagement of the switch blade 18 from the left-hand jaw 26, the coil and switch parts will continue their movement. As soon as the magnet coil 8 has moved beyond the middle point of the core member 5, the energy stored in the spring 24 will cause the movement to continue until the coil 8 and the switch member 17 occupy the respective position indicated by the broken lines in Fig. 1.

The above described movement of the switch blade interrupts the supply of energy through the resistor 29, and, therefore, the thermostat 30 will soon be disengaged from the contact 31 and finally engage the contact 32. When this occurs, the circuit will again be established through the magnet coil as hereinbefore described, and the coil will move from its left-hand position, indicated by the broken lines in Fig. 1, to its right-hand position indicated by the full lines in Fig. 1.

It may be noted that the thermostat circuit is not interrupted by the movement of the member 30 but is interrupted by the disengagement of the blade 18 from the jaws 26, thus insuring that there shall be substantially no pitting of the thermostat contacts.

The device embodying my invention thus provides a single reciprocally movable coil to actuate a switch member to close and interrupt a circuit through a resistor. It may be noted that the entire assembly of the switch may be made relatively compact and that there are but few moving parts, which may be made relatively rugged and adapted to be operated a large number of times without causing any appreciable wear in the operating parts. Even if these parts wear,

the device will operate substantially as when new, to close and interrupt an electric circuit.

Various modifications may be made in the device embodying my invention without departing from the spirit and scope thereof and I desire that only such limitations shall be placed thereon as are limited by the prior art or are specifically set forth in the appended claims.

I claim as my invention:

1. In a switch, the combination with a movable blade, a plurality of stationary jaws, a reciprocally slideable magnet coil, resilient means for operatively connecting said movable blade to said magnet coil, of means for causing said coil, upon the energization thereof, to selectively engage said stationary jaws, said means comprising a core member adapted to have said coil slide thereon, said core member having a central magnetic portion and two non-magnetic end portions, and said resilient means being adapted to normally maintain said coil at one of said non-magnetic end portions and to cause said coil when energized to move past said magnetic portion.
  2. In a switch, the combination with a plurality of stationary jaws and a movable blade adapted to selectively engage said jaws, of means for actuating said blade to selectively engage said jaws comprising an elongated guide and core member, said guide member having a central magnetic portion and two non-magnetic end portions, a magnet coil reciprocally slideable on said guide for actuating said blade, and a spring member operatively engaging said coil and blade for normally maintaining said coil at one of said non-magnetic end portions and adapted to cause said coil when energized to move past said magnetic portion.
  3. In a switch, the combination with a plurality of stationary jaws and a movable blade adapted to selectively engage said jaws, of an elongated guide and core member comprising a central magnetic portion and two non-magnetic end portions, and a magnet coil reciprocally slideable on said guide for actuating said blade.
  4. In a switch, the combination with a plurality of stationary jaws and a movable blade adapted to selectively engage said
- jaws, of a magnet coil adapted to actuate said blade, an elongated guide and core member for said magnet coil comprising an intermediate magnetic portion and two non-magnetic end portions, said coil being adapted when energized to move on said guide from one end thereof to substantially its middle portion, and an energy-storing means associated with said coil and blade and adapted to store energy during the movement of said coil and to cause said coil to move past said magnetic portion to the other end of said guide, whereby said blade is disengaged from one of said jaws and interrupts the circuit through said coil.
5. In a switch, the combination with a movable blade and a plurality of stationary jaws, of means for causing said blade to selectively engage said jaws, said means comprising a centrally located magnetic core and guide member having nonmagnetic end portions, a single magnet coil operatively engaging said movable blade and movable to a substantially central position on said guide member when energized, and means associated with said coil and blade for storing energy during said movement, said energy storing means causing a continuation of the movement of said coil and blade.
6. In a switch, the combination with a movable blade and a plurality of stationary jaws adapted to be selectively engaged by said blade, of means comprising a single movable magnet coil and a composite guide and core member for disengaging said blade from one of said jaws, said composite guide and core member having a central magnetic portion and two non-magnetic end portions.
7. In a switch, the combination with a movable blade and a plurality of stationary jaws adapted to be selectively engaged by said blade, of means comprising a single movable magnet coil, a composite guide and core member, having a central magnetic portion and two nonmagnetic end portions, and an energy-storing means for causing said switch blade to move past said magnetic portion and to selectively and alternately engage said switch jaws.

In testimony whereof, I have hereunto subscribed my name this 15th day of March, 1921.

FRANK F. FORSHEE.
